MAP AND LIKE ARTICLE SUPPORT

Johnse H. Beck, Indianapolis, Ind., assignor to
 The Geo. F. Cram Company, Indianapolis, Ind.,
 a corporation of Illinois

Application December 17, 1938, Serial No. 246,342

8 Claims. (Cl. 248—224)

My invention relates to improvements in supporting means for spring rollers of the type particularly adapted for receiving maps, curtain shades, and like articles.

One of the objects of the invention is to provide a supporting member which may readily be attached to the wall or other supporting background capable of receiving a roller frame in such a manner that the spring roller frame may tilt, thereby preventing the maps or other articles carried on the roller frame from running crookedly on the roller and which, at the same time, while permitting a ready removal of the frame from the supporting member will also prevent the supporting frame and accompanying roller from being accidentally dislodged during the rolling and unrolling of the maps.

For the purpose of disclosing my invention, I have illustrated an embodiment thereof in the accompanying drawing, in which:

Fig. 1 is a front elevation of a map support embodying my invention;

Fig. 2 is a rear elevation of the supporting block;

Fig. 3 is a sectional view on the line 3—3 of Fig. 2 showing the device attached to a wall or other support;

Fig. 4 is a front elevation of the roller supporting frame showing the supporting block in dotted lines for the purpose of illustrating more fully the operation thereof;

Fig. 5 is a front elevation of a modified form of my supporting block; and

Fig. 6 is a sectional view on the line 6—6 of Fig. 5.

In the embodiment of the invention illustrated, the roller supporting member comprises an elongated supporting bar 1 provided along its length at its upper and lower edges with rearwardly and downwardly turned flanges 2. These provide lips 3 at the rear of the bar 1 and are spaced apart from the bar. At each end of the bar, I provide supporting brackets 4 having angularly extending bases 5 by which the same may be bolted to the front face of the bar. These brackets support a spring roller 6 adapted to receive the maps. This roller is of the usual spring roller type of support now in commercial use, both as shade rollers and map rollers and the structure is such that, due to the tension of the spring within the roller, the maps carried thereon may be unrolled and the spring placed under tension. Thus, when the roller is released, it will again roll the maps up. As is usual in structures of this character, one of the brackets for sup-

porting this roller 6 is provided with an ordinary round opening and the other is provided with a slotted or squared opening for receiving the pins of the roller.

This structure is adapted to be supported from a supporting block 7 provided on its rear face with spacer bosses 8 or other similar spacer members which are preferably adapted to surround the bolt receiving openings 9 extending through the block. These spacer webs are provided so that the block itself will be slightly spaced from the wall or other supporting members to which the block is adapted to be secured for purposes which will more fully hereinafter appear. The supporting block 7 is provided on its upper edge 10 with a substantially flat surface 10 and rounded corners 11. The bottom edge 12 of the block is substantially straight and parallel with the edge 10 and at its two ends this edge is inclined upwardly as at 13. The space between the flanges 3 is just sufficient to permit the insertion therein of the block 7. This block 7 has projecting from its upper edge a pair of slightly longitudinally spaced pins 14 adapted to enter pin-receiving openings 15 in the top of the flanges 2. 25

In operation, the supporting block 7 is adapted to be secured against the wall or other supporting surface and it will be noted that due to the bosses 8, this block will be spaced apart from the supporting surface. The supporting bar is then hooked over the block, the block entering between the spaced apart edges of the lips 3 and the pins 14 being adapted to project through the openings 15 in the top of the bar. Due to the fact that the top edges of the block are rounded off at the points 11 and the lower edges are tapered off at the point 13, the supporting bar can rock on the block so as to accommodate itself to the pull on the maps in unrolling the same, thereby permitting the roller to always run true. 40

In the modified structure illustrated in Figs. 5 and 6, the block 7 is formed on a hollow base 16 through the medium of a web 17 which will space the block 7 from the base 16. This base projects at the points 18 and 19 beyond the sides of the block 7 and is provided with screw openings 20 whereby the same may be secured to the wall or other supporting foundation.

However, in both structures, the block is spaced from its support to accommodate the inturned flanges 3 of the supporting bar.

Due to the construction disclosed, it is practically impossible to accidentally dislodge the supporting bar 2 from the supporting block 7. When the bar 2 is rocked on the block, as indi- 55

cated in Fig. 4, the pins 14 are of sufficient length to insure both pins projecting through the openings. Furthermore, due to the fact that the bottom inturned flange 3 is provided, if for any reason the unrolled maps are released by the operator and allowed to fly back into rolled position, there will be no danger of the bar jumping off of the block because of the fact that any vertical jumping movement imparted to the bar would tend to lock the lower flange 3 of the bar behind the bottom edge of the block.

Therefore, it is practically impossible to accidentally dislodge the bar from the supporting block although the supporting bar may readily be removed from the supporting block when desired.

I claim as my invention:

1. In a support for maps or the like, the combination with a roller supporting bar having a channelled recess on its rear face and an opening in the top wall of said recess intermediate of its ends, of a supporting block, and a pin projecting from the top edge of said block adapted to enter the opening in the top wall of the supporting bar, said recess being of sufficient size to receive said block.

2. In a support for maps or the like, the combination with a roller supporting bar having a channelled recess on its rear face and a pair of spaced apart openings in the top wall of said recess intermediate of its ends, a supporting block, a pair of spaced apart pins projecting from the top edge of said block and adapted to enter said openings, said recess being of sufficient size to receive said block.

3. In a support for maps or the like, the combination with a roller supporting bar having a channelled recess in its rear face and an opening in the top wall of said recess, of a supporting block and a pin projecting from the top edge of said block adapted to enter said opening, the vertical width of the block being less than the total width of the channel to permit said bar to rock on the top edge of said block.

4. In a support for maps or the like, the combination with a roller supporting bar having a channelled recess on its rear face and a pair of spaced apart openings in the top wall of said recess, of a supporting block and a pair of spaced apart pins projecting from the top edge of said block and adapted to enter said openings, the vertical width of the block being less than the total width of the channel to permit said bar to rock on the top edge of said block.

5. In a support for maps or the like, the combination with a roller supporting bar having a channelled recess in its rear face and inturned lips at the rear edge of said recess, the top wall of said channel having an opening therethrough, of a supporting block, means for spacing said bar from a support to which it is to be attached and a pin projecting from the top edge of said block adapted to enter said opening, the vertical width of said block being such as to permit the same to be inserted into said recess through said inturned lips.

6. In a support for maps or the like, the combination with a roller supporting bar having a channelled recess in its rear face, the edges of said recess having inturned lips and the top wall of said recess having a pair of spaced apart openings therein, of a supporting block, means for spacing said block from a support to which it is adapted to be attached and a pair of pins projecting from the top edge of said block adapted to enter said openings, the top edge of said block having its outer ends inclined downwardly and the vertical width of said block being such as to permit the same to pass between said inturned lips.

7. In a support for maps or the like, the combination with a supporting bar having a channelled recess in its rear face provided with inturned lips and having a pair of spaced apart openings in the top wall of said recess, of a supporting block from a support to which it is adapted to be attached and a pair of upwardly projecting pins on the top edge of said block adapted to project through said openings the vertical width of said block being such as to permit it to pass between said inturned lips and said block being tapered toward its side edges.

8. In a support for maps or the like, the combination with a roller supporting bar having a channelled recess in its rear face provided with inturned lips and having a pair of spaced apart openings through the top wall thereof, of a supporting block, means for spacing said block from a support to which it is adapted to be attached, a pair of spaced apart pins projecting from the top edge of said block and adapted to enter said openings, said block having its top and bottom edges rounded at its outer ends and having a vertical width permitting the same to pass between the inturned lips.
